DARNING DEVICE

Max D. Baumgart, New York, N. Y.

Application March 29, 1949, Serial No. 84,149

4 Claims. (Cl. 139—33.5)

1

This invention relates to manually operated darning lasts or devices and has for its object the provision of such device which will be simple and inexpensive to manufacture and whose operation will require no skill, so that the device may be used by inexperienced persons.

With these objects in view my invention consists of the novel combination, construction and arrangement of parts as will be presently described and defined in the appended claims.

In the accompanying drawing that constitutes part of this specification and in which similar reference characters denote corresponding parts:

Fig. 1 is a perspective view of the device in position of use and showing the darning operation;

Fig. 2 is a vertical section on line 2—2 of Fig. 1.

Fig. 3 is an enlarged section on line 3—3 of Fig. 2 seen in the direction of the arrows, and

Fig. 4 is a similarly enlarged cross section on line 4—4 of Fig. 3.

Referring in detail to the drawing, the device 10 is composed of two complementary semi-ovally curved plates 11, 12 of about equal size which are adapted in assembled or operating position to be in the same plane, with the diametrically extending straight edges 11a, 12a, opposite one another. These plates are each provided on their curved circumferences with a groove 21a, in which fits a rubber ring 21, or the like adapted to hold the two plates resiliently assembled and to clamp the edges of the material M to be darned between said plates during the darning operation.

Permanently fixed to the lower part of one of the plates, as 11, is a block 13 of any suitable material, whose bottom edge 13¹ extends parallel to and is even with the straight edge 11a thereof. Fixedly mounted in this block 13, are a number of uniformly spaced members 15 projecting transversely through said block and outwardly a suitable distance, each member being formed at its outer end with a forwardly curved hook portion 15a.

The upper face of said block is formed with a circularly curved longitudinally extending groove 13a serving as socket for a cylindrical member or roller 14. This roller is rotatively held in position on said block by metal straps 16 or the like. Fixedly mounted on this roller 14 and projecting transversely and outwardly from this roller are another series of similar hook shaped members 17. These members are uniformly spaced similar to hooks 15 and project through transversal slots 13², provided in the block 13 and ex-

2

tending throughout the height of the latter, permitting the series of hook members 17 to be swung forwardly and rearwardly through said block, as best shown in Fig. 4. The swinging of the hooks 17 may be best effected by a finger 18 fixed to and projecting upwardly from the roller 14 and which under the action of a plate spring 19 or the like has the tendency to hold the hooks 17 out of alignment with the series of hooks 15.

10 The operation is as follows:

After clamping the material M between the two plates with the hole H to be darned somewhere below the hooks, the thread t is successively stitched along the edge of the hole H, drawn across the latter and passed over the opposite hooks, alternately in opposite directions to form warps. When the hole H has been entirely covered by the warps, the weft thread t¹ is passed transversely alternately from one side to the other, through the warp shed formed between the hooks 15 and 17, which shed is formed by turning the roller alternately in opposite directions, as indicated in Figs. 2 and 4.

25 The finger 18 may be conveniently manipulated by hand or by means of a string 20 attached thereto and suitably looped around the user's foot.

What I claim is:

1. A manually operable darning last or device, comprising a pair of plates adapted to be resiliently joined to clamp the material to be darned between them, a member fixed to one of said plates, a series of hooked elements fixed thereon in a uniformly spaced relationship, a cylindrical member rotatably borne on said fixed member, a similar series of hooked elements fixed on said rotatable member in a similar uniform spaced relationship, said hooked elements being adapted to support lengths of a thread to form warps, said second series being adapted to be swung rearwardly and forwardly to form a warp shed between themselves and the fixed elements for the alternate passage of a weft thread through the warp shed after the hole of the material has been covered by said warps, and means for turning the said turnable member.

2. In a manually operable darning last or device, according to claim 1, in which the two plates are semi-ovally curved circumferentially and each has a straight base, said curved circumferences being each grooved, and a rubber ring adapted to fit in said grooves to resiliently join said plates in assembled position and clamp the edges of the material to be darned between the said straight bases of the said plates.

3. In a manually operable darning last or device, according to claim 1, in which the member fixed to one of said plates is transversely slotted for the passage of said second series of hooked elements, permitting the latter to be swung forwardly and rearwardly.

4. In a manually operable darning last or device according to claim 1 in which a spring urged finger projects from said rotatable member, for the manipulation of the latter.

MAX D. BAUMGART.
